(57) **CLAIM**

The ornamental design for a cap for container corner casting, as shown and described.

DESCRIPTION

FIG. 1 is a front view of a new design for a cap for container corner casting.

FIG. 2 is a right side view thereof.

FIG. 3 is a top view thereof.

FIG. 4 is a bottom view thereof; and,

FIG. 5 is a perspective view thereof.

Thin lines shown in the drawings are intended to represent the three-dimensional contour of the design, and are not intended to indicate surface decoration.

The left view is omitted because it is symmetrical with the right view.
